(21) Appl. No.: **29/447,573**

* cited by examiner

(22) Filed: **Mar. 5, 2013**

Primary Examiner — Wan Laymon

(51) LOC (10) Cl. **24-02**

(57) **CLAIM**
The ornamental design of a phacoemulsification handpiece, as shown and described.

(52) U.S. Cl.

DESCRIPTION

USPC **D24/144; D24/133**

(58) **Field of Classification Search**

FIG. 1 is an isometric view of the phacoemulsification handpiece of present invention.

USPC D24/144, 133, 112, 146; 604/22, 604/27-28, 30, 39; 606/166-167, 169-170

See application file for complete search history.

(56) **References Cited**

FIG. 2 is a top view of the phacoemulsification handpiece of the present invention.

U.S. PATENT DOCUMENTS

FIG. 3 is a first side view of the phacoemulsification handpiece of the present invention.
